DESIGN FOR A MULTIPLE CANDY BOX

Irving A. Deline, Denver, Colo.

Application February 15, 1935, Serial No. 55,451

Term of patent 7 years

To all whom it may concern:

Be it known that I, Irving A. Deline, a citizen of the United States of America, residing at Denver, in the county of Denver and State of Colorado, have invented a new, original, and ornamental Design for a Multiple Candy Box, of which the following is a specification, reference being had to the accompanying drawing, forming part thereof.

The drawing illustrates a perspective view of the design.

The characteristic features of my design reside

in a large outer box having a tapering opening in front and containing a series of superimposed smaller boxes arranged in a plane parallel to the top and bottom of the outer box; the outer box having flanged top and bottom sections, the top of the box having stepped panels decreasing in area toward the center substantially as shown.

I claim:—

The ornamental design for a multiple candy box, as shown and described.

IRVING A. DELINE.
